CLAIM

The ornamental design for a wrist band, as shown and described.

DESCRIPTION

FIG. 1 illustrates a perspective view a wrist band showing the new design;

FIG. 2 illustrates a first side view thereof;

FIG. 3 illustrates a second side view thereof;

FIG. 4 illustrates a front view thereof;

FIG. 5 illustrates a rear view thereof;

FIG. 6 illustrates a top view thereof; and,

FIG. 7 illustrates a bottom view thereof.

The broken lines in the drawings depict portions of the wrist band that form no part of the claimed design.
